UNITED STATES PATENT OFFICE.

CHARLES FRANZ, OF NEW YORK, N. Y., ASSIGNOR TO A. A. VANTINE & CO.,
OF SAME PLACE.

DESIGN FOR WOVEN FABRIC.

SPECIFICATION forming part of Design No. 33,093, dated August 14, 1900.

Application filed July 20, 1900. Serial No. 24,342. Term of patent 3½ years.

all whom it may concern:

Be it known that I, CHARLES FRANZ, a subject of His Majesty the Emperor of Germany, and a resident of New York, (Jamaica,) county of Queens, State of New York, have invented and produced a new and original Design for a Woven Fabric, of which the following is a specification, reference being had to the accompanying drawing, forming part thereof, in which is represented a plan view of a piece of fabric embodying my design.

The leading feature of the design consists of three panels A, B, and C, all alike, situated A at the left end, B in the center, and C at the right end of the design. Each panel is composed and made up of two rows of spade-shaped figures D, with four rosettes F, containing two smaller rosettes, within each other.

There are also four birds G, facing a half-rosette design H, which contains two semi-circles built from two heart-shaped figures, one within the other, and finished off with two conventional oval-shaped figures, all resting on a vine of leaves.

Other features of the design consist in panels I and J, in which there are four conventional Indian peacocks K, decorated with various leaves.

I claim—

The design for a woven fabric herein shown and described.

CHARLES FRANZ.
